Primary Examiner — Cynthia M. Chin(57) **CLAIM**

The ornamental design for a kids scooter, as shown and described.

DESCRIPTION

FIG. 1 is a front and right side perspective view of a kids scooter showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear and right side perspective view thereof;

FIG. 9 is a right side view in an alternate configuration with the seat and t-shaped handle removed;

FIG. 10 is a right side view in an alternate configuration with the seat and y-shaped handle removed;

FIG. 11 is a right side view in an alternate configuration with the t-shaped handle removed; and,

FIG. 12 is an exploded view thereof.

The broken lines in the drawings illustrate the portions of the kids scooter, which form no part of the claimed design.
